ADJUSTABLE FAN TOY

Felix Gilbert, New York, N.Y., assignor to De Luxe
Topper Corporation, a corporation of Delaware

Filed Jan. 4, 1967, Ser. No. 5,305

Term of patent 3½ years

(Cl. D34—15)

FIG. 2

FIG. 3

FIG. 4

FIG. 5

FIG. 6

FIG. 7

FIG. 1 is a perspective view of an adjustable fan toy, showing my new design;

FIG. 2 is a top view;

FIG. 3 is a right side elevational view;

FIG. 4 is a front view;

FIG. 5 is a rear view;

FIG. 6 is a left side elevational view; and

FIG. 7 is a bottom view.

I claim:

The ornamental design for an adjustable fan toy, substantially as shown.
